UNITED STATES PATENT OFFICE

WILLIAM D. CARTER, OF LAKEWOOD, OHIO, ASSIGNOR TO THE CARTER PRODUCTS CORPORATION, OF CLEVELAND, OHIO, A CORPORATION OF OHIO

DEVICE FOR CLEANING WINDOWS

Application filed February 4, 1929. Serial No. 337,191.

This invention relates to devices for cleaning windows or other glass surfaces and has for its object to provide a complete unitary structure for cleaning windows which is simple in construction and economical to manufacture.

A further object is to provide a device for the purpose stated which is easily assembled and disassembled and capable of being enclosed in a small compact package for shipping and marketing.

A further object is to provide a window cleaning device which operates effectively as such and which includes means for drying as well as wetting the glass so that the entire operation of cleaning may be accomplished by the use of the one unitary device.

With these and such other objects in view as will be apparent from the following description, the invention resides in all the novel features of construction and combination of parts hereinafter described and particularly pointed out in the appended claims.

In the accompanying drawing, Fig. 1 is a front elevation of the device assembled; Fig. 2 a rear elevation of the same; Fig. 3 is a top plan view of the cleaner; Fig. 4 a vertical section on line 4—4 of Fig. 2 and Fig. 5 is a front elevation of the handle attaching means with the liquid container removed.

Describing the invention in detail and referring to the various parts by reference numerals, 10 designates the liquid receptacle which is made from two rectangular sheet metal stampings 11 and 12 oppositely dished with three of their edges including the two ends and the one side folded and pressed together forming a continuous bead 16. The remaining free edges 17 and 18 of the members 11 and 12 are spaced apart and between these edges is clamped a felt pad 20 which constitutes the washing member. The pad 20 is clamped between the edges 17 and 18 by bolts 21 which pass therethrough and thru the pad 20 by nuts 22. The felt pad 20 projects outwardly from the ends as well as from the flanges 13 and 14 a substantial distance. In the front face 11 of the container an opening 19 is provided for filling the same with water or other cleaning fluid which opening may

be closed by any suitable stopper or cover. This liquid container 10 with the felt pad 20 through which the liquid passes by capillarity constitutes the means for applying the fluid for wetting the glass and for loosening the dirt thereon so that it may be subsequently removed by the squeegee 25 forming part of the device.

The squeegee 25 is composed of the rubber strip 26 having one edge mounted in a sheet metal holder 27.

For securing the squeegee 25 to the container 10 and also for securing the handle 28 thereto, an attaching member 30 is provided. The member 30 which is a sheet metal stamping comprises a body portion 31, one end of which has lateral extensions 32 which extensions are bent to form U-shaped clamping jaws 33. Struck from the rear edge of the extensions 32 are lugs 34 arranged to engage over the bead 16 of the container 10. The opposite end of the body portion 31 terminates in laterally extending arms 35 which are provided with apertures 36 spaced to engage over the bolts 21 which secure the pad 20 in the container 10. The body portion 31 is provided with an aperture 37 with the material about said aperture pressed outwardly to form a depressed seat 38 in which the flared end 39 of the handle 28 seats. The handle 28 is in the form of a split tube with one end 39 flared outwardly. In flaring the end 39 a V-shaped notch 40 results at the split 41. This V-shaped notch engages over a lug 42 formed on the tapered seat 38 of the attaching member 30 which lug is preferably formed by striking up a portion of the metal forming the seat 38. The handle is somewhat resilient so that after the same is pressed into the aperture 38 the slit permits the tube to expand so that it fits closely therein, the lug 42 when engaged in the V-shaped notch 40 prevents rotation of the handle in its seat.

In assembling the device, the handle 28 is slipped in place in the aperture 37 with the lug 42 fitting in the V-notch in the seat 38. The lugs 34 on the extensions 32 are then engaged over the head 16 of the container 10 and with the nuts 22 removed from the two

center bolts 21 the ends 35 are engaged over these bolts and the same is secured in place by the nuts 22. As the body portion 31 of the attaching member 30 is bent to conform to the shape of the container 10 and made to fit closely thereagainst, the flared portion 39 of the handle is securely clamped in place between the side 12 of the container and the member 30. The device is easily assembled, and when disassembled forms a very compact package. While the member 28 is termed a handle in this description, it is apparent that this member may be merely a socket into which a long handle may be engaged.

15 It will be noted that the container is in no manner modified for securing the handle in place, the bolts 22 being the necessary fastening means for the felt pad. By this construction the cost of making the device is kept at a minimum.

The operating of the device is apparent. The container 10 is filled with water or other suitable cleaning fluid through the filler opening 19. By capillary action this liquid is supplied to the outer edge of the pad 20. By rubbing the same over the window pane or other surface to be cleaned the dirt is loosened, and by merely turning the device around the dirt and moisture are wiped from the surface by means of the squeegee 25.

It will be noted that the squeegee attaching member 30 and the receptacle 10 together constitute the means for attaching the handle socket 28.

35 Having thus described my invention, what I claim is:—

1. In a fountain window washer, the combination with a water container having a projecting seam at one portion of its periphery and a clamping bolt at the opposite side thereof, of a handle support comprising a plate disposed against one side of the container and engaged with said seam and held by said bolt, and a handle having an end clamped between the plate and said container.

40 2. In a fountain window washer, the combination with a water container having a projecting seam at one portion of its periphery and a clamping bolt at the opposite side thereof, of a handle support comprising a centrally apertured plate disposed against one side of the container and having fingers engaged with said seam and an aperture receiving said bolt, and a handle disposed through said central aperture of said plate and having a flared end clamped between the plate and the container.

45 3. In a fountain window washer, the combination with a liquid container having a projecting seam at one portion of its periphery and a clamping bolt through the opposite portion thereof, of a handle support squeegee holder comprising a centrally apertured plate disposed against one side of the container and having an inwardly flared

flange surrounding said central aperture, the wall of said flange having a notch, a handle disposed through said aperture having a flared end held against the container by the first flange and having a pin engaged in said notch to prevent rotation of the handle, the plate having an opening receiving said bolt, and fingers on the plate engaged with said seam.

4. A handle attaching means for the water container of a window washer comprising a plate having fingers at one side for detachable engagement with an edge of the said container and having means for detachably securing the other side of the plate to another edge of the container, said plate having a central opening provided with a surrounding outwardly converging flange, and a handle disposed through said opening and having a flared end held against the container by the said flange.

5. In a cleaning implement, an apertured supporting plate, a reservoir overlying said plate, a handle passing through said aperture, and a flange on said handle disposed between said plate and said reservoir.

In testimony whereof, I hereunto affix my signature.

WILLIAM D. CARTER.
